ELECTRICAL CONNECTOR HAVING
RESILIENT INSERTSJakob R. Frei and William A. Uline, Sidney, N. Y.,
assignors to Bendix Aviation Corporation, New
York, N. Y., a corporation of Delaware

Application September 20, 1945, Serial No. 617,560

6 Claims. (Cl. 173—328)

1

This invention relates to electrical connections and the means for making them.

Prior connections were in general subject to breaking under bending stresses, to easy separation, and to rapid disintegration by vibration.

It is an object of the invention to make pin and socket connectors of a new and improved type and in particular to avoid the necessity of machining pins, which is an expensive operation, particularly when applied to small size materials. Another object of the invention is to afford protection to pin and socket connections against blows and crushing or bending stresses, while maintaining resilience in the mounting of the connection. Another object is to protect and reinforce the joints between the soldered ends of wires or other electrical conductors and the connectors to which they are attached. Yet another object is to assemble the several parts of a connection in units, all the parts of which cooperate to produce a new and useful result.

The above and further objects and novel features of the invention will more fully appear from the following detail description when the same is read in connection with the accompanying drawings. It is to be expressly understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a longitudinal section through the socket bearing part of the connection;

Fig. 2 is a longitudinal section through the pin bearing part of the connection;

Fig. 3 is a perspective detail of a rubber buffer;

Fig. 4 is a section detail of a socket type connector; and

Fig. 5 is a sectional detail of a pin type connector.

Figs. 1 and 2 have been designed to show the operative relationship of the socket insert assembly and the pin insert assembly of a novel connection. The connection involves a pin connector and a socket connector which have cooperating tight fitting surfaces that provide for the efficient transmission of electrical current. The assembly contains one or a plurality of connector elements, each of which is of copper or some other metal having good electrical conducting properties, that is preferably silver plated on its surface, and that may be mounted in a re-

2

silient dielectric block which is in turn mounted within a metallic protecting shell. The ends of the connector elements to which the wires are to be attached project beyond the block or insert and have solder wells to receive the ends of the wires. The projecting ends and the wire joint are given protection by inner and outer supporting means, the inner of which is called for convenience a support or buffer and the outer of which is called a grommet. The inner member may be channeled to receive the ends of the sockets and the ends of the wires, in which case a grommet having a smooth inner surface may be employed, or the grooves may be formed on the interior of the grommet and a rounded support may be employed between the joints.

In Fig. 1 is shown a section of a socket insert assembly comprising a grommet 10 which is adapted to fit over and enclose a support 11 having four vanes or ribs 12 which bound four longitudinal grooves 13 in the surface of the support. At the end of the support the crossed ribs 14 are formed for cooperation with crossed depressions in the end of the insert. The support in end view therefore has somewhat the appearance of a cross patee with rounded bars and approximately semi-circular grooves between the bars.

The insert, as shown in Fig. 1, is composed of a block 20 of rubber or other resilient dielectric material having an appropriate number of holes to receive sockets 21. In the particular form of the device which is illustrated in the drawings, four sockets are included in the socket assembly and four cooperating pins are mounted in the pin assembly. The said holes are enlarged at one end to receive flanges 22 on the ends of the sockets and the shoulders formed by the enlargement of the holes cooperate with the flanges as abutments to position the sockets in the insert. The sockets 21 project beyond the inner end of the insert 20, and there is formed between them in the end of the insert a pair of crossed grooves 23 in which the crossed ridges 14 of the support are adapted to be seated. Prior to the seating of the support 11 between the projecting ends of the sockets, cement may be applied in order to integrate the support with the insert. The size of the buffer is such that the walls of the socket bulge slightly beyond the circumference thereof, a feature that is important from the standpoint of protection and strength. The engaging and interference of this cross in its mating member improves creepage and flashover between contacts and permits the use of higher voltages

for the same contact spacing than is feasible with prior art designs.

The sockets as shown in Figs. 1 and 4 are preferably tubular, having flanges 22 peened at their ends and being pinched together in a plurality of places 24 about a midportion of the tube. Pinching of the tube is accomplished by swaging, preferably at three points 120 degrees apart, the swaging being carried out to such an extent that light does not show through the inner diameter. By this means a stop is provided that prevents solder from passing beyond the solder well 25 into the portion of the connector that is designed to receive the pins. The sockets may be cemented in place in the insert if desired. The indented parts of the tube 21 act to restrain the motion thereof with respect to the insert 20, because the resilient material of the insert makes its way to some extent into the dents, particularly when an internal annular ridge is provided in the insert.

The novel socket connector may be assembled as follows, although other orders of steps may be followed if advantage is gained thereby: The sockets 21 are pushed into the insert, the diameter of the holes of the insert being preferably somewhat less than the diameter of the sockets so that forced fit is obtained in the resilient dielectric material of the insert. The sockets are emplaced in the insert 20 with the open sides of the wells 25 facing outwardly, the grommet 10 is passed over the wires, and the conductor wires 26 are soldered in place. The crossed ribs 14 of support 11 are now mounted in crossed groove 23, and receive the wires 26 in grooves 13. The grommet is passed over the support. Because of their size the sockets bulge beyond the side of the support and the grommet tends to press them firmly against the support so that the joints are held firmly but resiliently and are protected from shock.

A similar novel mounting is employed for the novel pin structure of Figs. 2 and 5. As shown in these figures, the pins are provided with a base member 30 having a well 31 at one end and a hole 32 at the other end, about which the flange 33 is formed as an abutment and for strength. Into the end 32 of the body portion 30 is soldered the two ends 34, 35 of a spring wire loop which has a silver plated surface. The sides of the loop are outwardly bowed as indicated at 36, and are provided with an exterior surface laterally curved to conform with the interior curvature of the socket. An advantage of this type of pin is that it may be manufactured by cutting sections from a length of wire drawn for the purpose, bending them to shape, and soldering them into position in the holder 30. Any springy metal can be used, or any non-metal provided it has the requisite strength, resilience, and electrical conductivity. A preferred material is beryllium copper, hard tempered at about 575° F. plus or minus about 10 degrees after shaping. It may contain about 1.9 to about 2.3% beryllium, the balance save for normal impurities, preferably less than .3%, being copper. The body portion of the pin has a groove 38 adapted to aid in holding the pins in position in the inserts. The insert 39 may be provided with a cooperating annular ridge to fit the groove, or the diameter of the holes through the inserts may be so small that the natural resilience of the insert fills the groove. The pin insert 39 has a face 40 that cooperates with a similar face 27 on the socket insert 20 so that when the parts are pressed closely together extraneous materials are excluded. This

construction improves creepage and flashover conditions and permits units with standard contact spacings to be used with higher voltages than heretofore.

5 The novel pin and socket assemblies are held in cooperating relation by a novel shell which serves to protect and to unite the parts of the connection. The protecting shell 50 for the socket insert assembly is adapted to be seated over the 10 grommet 10, and preferably to hold it under compression, as by means of a forced and conical fit with the end portion 51 of the shell. The shell is exteriorly provided with a shoulder 53 to serve as a means of purchase for a nut 54 having internal screw threads. The end of the shell 50 projects as a sleeve 55 that is provided with a slot 56 which is adapted to receive a cooperating key formed in the surface of the cooperating shell of the pin insert assembly. A 15 split metal ring 57 of stainless steel or other satisfactory material is mounted in an annular groove in the insert 20, projects therefrom, and is received in a groove 58 in the interior of the shell. The ring may be snapped into a pre-formed groove in the insert or molded in place.

20 The shell 60 for the pin insert assembly has external screw threads 61 adapted to cooperate with the screw threads in the nut 54. A key 62 is provided on the shell 60 for cooperation with 25 slot 56 in sleeve 55. The end of shell 60 forms a sleeve cooperating with sleeve 55, so that breaking strains are ineffective at the joint. A split ring 63 mounted in a groove in the insert and projecting into a groove in the shell serves to 30 align the parts longitudinally as the key 62 serves to align them angularly. The pin insert must be 35 aligned with the key and the socket insert with the slot so that the pins and sockets will be aligned automatically when the key and slot are 40 aligned.

The end of the sleeve 60 is twice reduced, once at 45 64 to form a seat for the tubular connecting member and shield 65, and once at 66 to form a seat for the tubular conical retainer 67 that holds the grommet 68 under compression against the block 39 and the ring 63. The mounting member 65 may be of steel spot welded or otherwise secured to the shell, and the retainer 67 may be of brass and brazed or otherwise secured to the 50 shell.

The shield 65 may be permanently attached to a supporting body and the shell 50 may receive the end of a cable, thus providing a connection of superior characteristics, but also both parts of the connector may be free, or the fixed mounting may be reversed.

The size of the inserts, buffers, and grommets and the location of the split rings on the inserts may be such that they are interchangeable in the shells.

60 An advantage of this connection is the protection afforded to the connecting elements so that bending and breaking strains, crushing stresses and sustained vibration are alike incapable of destroying the connection, which is capable of functioning even when heavy blows have materially deformed the outer shell. Other advantages are inherent in the novel construction of the tubular socket and the pin connector. Particular advantages are obtained in increased ease of manufacture. Another advantage of the invention is the reinforcement afforded to the joints between conductors and pins and sockets. Because of this reinforcement, connectors of relatively fragile kind may be employed. Another advan-

tage of the invention is the presentation of a line connection which has electrically conductivity of a high order. Another advantage of the invention is in a pin that needs no machining but that may be drawn as wire, cut to size, and bent to shape. A further advantage of the invention is in a socket that is made of simple materials by simple operations. A particular advantage is in the combination of the spring pin and tubular socket of simple type, which are electrically efficient, mechanically strong, and easy and inexpensive to make. Other advantages of the invention will be in part apparent and in part deduced from the specification hereinabove.

Although only one embodiment of the present invention is herein illustrated and described, it is to be expressly understood that the same is not limited thereto. Various changes may be made therein, particularly in the design and arrangement of the parts illustrated without departing from the spirit and scope of the invention, as will now be apparent to those skilled in the art.

What is claimed is:

1. In an electrical connector of the pin and socket type, contact members mounted in a resilient insert and being of such length that their ends project from at least one end of said insert, a rubber support mounted within the said projecting ends and in a recess of cooperating shape in the insert, a rubber grommet enclosing said projecting ends and said support, and a metallic shell protectively and compressively mounting and enclosing the insert and grommet and provided with means to hold the parts in 35 cooperating relation.

2. In an electrical connector of the pin and socket type, contact members mounted in a resilient dielectric insert and having ends that project from the insert, a resilient dielectric support mounted within said projecting ends, a resilient dielectric grommet enclosing and protecting said support and said projecting ends, and a metallic shell compressively and protectively enclosing and mounting the insert and grommet 45 and provided with means to hold the parts in cooperating relation.

3. In an electrical connector, a rigid tubular shell having an internal cone-like wall portion, a resilient insert in said shell having a plurality of passages therethrough, a rigid contact having a close fit in each of said openings and projecting beyond one end thereof, a flexible conductor electrically connected to the projecting end of each contact, a support of resilient material centrally disposed with respect to said projecting ends and said flexible conductors to act as an internal support therefor, a tubular grommet of insulating material surrounding said support and having engagement externally with said cone-like wall portion, the adjacent surfaces of said support and grommet being so formed as to provide passages in which said flexible conductors are resiliently gripped, and means engaging oppositely facing grooves in said shell and insert 65 for removably retaining said insert in the shell and in compressed end to end contact with said support and grommet, and for holding said grom-

met under pressure against said cone-like wall portion.

4. In an electrical connector, a rigid shell having a cone-like internal wall portion and a cylindrical portion, a contact supporting resilient insert having a close fit in said cylindrical portion and a plurality of passages therethrough for electrical contacts, a resilient tubular grommet in said cone-like portion of the shell, a resilient support within the grommet, the adjacent surfaces of said support and grommet being such as to provide passages forming extensions of the passages in said insert, and means engaging an external groove in said insert for supporting the same in the shell and in compressive end to end contact with said support and grommet.

5. In an electrical connector, a rigid shell having an internal cone-like portion and a cylindrical portion, a contact supporting resilient insert having a close fit in said cylindrical portion and a plurality of passages therethrough for electrical contacts, a resilient tubular grommet engaging the wall of said cone-like portion, a resilient support within the grommet, said support having external grooves therein which cooperate with the internal surface of said grommet to form passages in line with the passages in said insert, and means for holding said insert in said shell in compressive face to face contact with said grommet and support.

6. In an electrical connector of the pin and socket type, contact members mounted in an insert and projecting from at least one end thereof, a resilient support between the projecting ends of said contact members and in abutting relation with the insert to reinforce said projecting ends, a conical grommet enclosing the support and said projecting ends, and a metallic shell compressively and protectively mounting and enclosing the insert and grommet and having means to hold the parts in cooperating relation, said shell also having a conical portion cooperating directly with said conical grommet.
